(57) **CLAIM**

The ornamental design for a light fiber mounting device, as shown and described.

DESCRIPTION

FIG. 1 is an isometric view of a light fiber mounting device showing our new design;

FIG. 2 is a left elevational view thereof, the right elevational view is a mirror image;

FIG. 3 is a front elevational view thereof, the back elevational view is a mirror image;

FIG. 4 is a top plan view thereof; and,

FIG. 5 is a bottom view thereof.

The broken line environmental showing is for illustrative purposes only and forms no part of the claimed design.
